BRACKET

Van L. Vendope, Dallas, Tex., assignor of thirty-three and one-third per cent to Richard Burdick and thirty-three and one-third per cent to Arthur S. Baron, both of Dallas, Tex.

Application January 23, 1936, Serial No. 60,384

3 Claims. (Cl. 173—328)

This invention relates to new and useful improvements in brackets.

One object of the invention is to provide an improved bracket which is particularly adapted 5 for use in supporting the usual "Lumiline" lamp.

An important object of the invention is to provide an improved bracket which is arranged to be attached to the ordinary "Lumiline" lamp without changing the structure of said lamp, 10 whereby the lamp may be connected with the ordinary electrical outlet terminal, the bracket serving not only as a support but also as an electrical connector, which eliminates the necessity of employing a separate specially constructed 15 bracket for illuminating the lamp.

Another object of the invention is to provide an improved bracket for a "Lumiline" lamp which is so constructed that a plurality of "Lumiline" 20 lamps can be placed in longitudinal alignment and electrically connected to a plurality of the usual electric sign receptacles or outlet terminals, the bracket being adjustable so that the connection may be readily made, irrespective of the 25 position or location of the receptacles.

A further object of the invention is to provide 25 an improved bracket for a "Lumiline" lamp, which bracket is secured to the usual removable caps of said lamp, whereby the lamp may be inserted between or removed from the caps without disturbing the bracket.

A construction designed to carry out the invention will be hereinafter described, together with other features of the invention.

The invention will be more readily understood 35 from a reading of the following specification and by reference to the accompanying drawing, in which an example of the invention is shown, and wherein:

Figure 1 is an isometric view of an ordinary 40 "Lumiline" lamp having a bracket, constructed in accordance with the invention, attached thereto.

Figure 2 is a view partly in elevation and partly in section, and showing the bracket engaged 45 in the usual electrical outlet terminal.

Figure 3 is an enlarged isometric view of one end of the lamp and bracket.

Figure 4 is a diagrammatical view showing a 50 plurality of the "Lumiline" lamps in longitudinal alignment and the connection by the brackets with the usual outlet terminals.

Figure 5 is an elevation showing how the 55 "Lumiline" lamps may be employed in forming a letter in an electric sign.

Figure 6 is a view similar to Figure 4, and showing a modified form of bracket, and

Figure 7 is a transverse, sectional view taken through one of the caps and showing another way of securing the bars to the caps.

In the drawing, the numeral 10 designates an ordinary "Lumiline" lamp such as is manufactured and sold by the General Electric Company. This lamp is cylindrical, being tube-like, and is made in standard lengths of 12 and 18 inches. 10 Each end of the lamp has a metallic terminal 11 which is formed with a central recess 12.

A flanged insulating cap 13 is adapted to fit over each terminal and this cap is provided with an annular spring contact 14. When the cap is 15 placed over the terminal, the contact 14 frictionally engages the wall of the recess 12 with a releasable snap-fastener effect to hold the cap on the end of the lamp and also to make electrical contact with the terminal. A metallic ear 20 or lug 15 of electrical conductivity extends outwardly from one side of each cap and this lug is preferably made integral with the contact 14. All of the above described parts are of standard manufacture and form no part of the present 25 invention. They have been described merely for the sake of clarity.

It is the usual practice to provide with each "Lumiline" lamp, a specially constructed base (not shown). This base has spring clips which 30 have electrical lead wires connected therewith, and the spring clips are arranged to receive the metallic lugs or ears 15. The base may be secured to a wall, or other suitable place. It is not only expensive to manufacture a base for 35 each lamp but it is impossible to electrically connect the lamp proper with the usual outlet terminal such as an attachment plug outlet, or sign receptacle. Therefore, the lamp cannot be used unless the specially constructed base is provided.

In carrying out the invention, a bracket 16 which not only serves as a support for the lamp, but also may be inserted in the usual electrical attachment plug outlet, whereby the lamp may 45 be connected with said outlet, is provided. The bracket includes a pair of flat electrical conductor bars 17. Each bar as shown has one end soldered, or otherwise suitably secured, to the inner side of one of the metallic lugs 15 provided on the 50 respective caps 14. The bar extends parallel to the lamp and has its opposite end bent outwardly from the lamp so as to form a prong 18. As is clearly shown in Figures 1 and 2, the bent meeting ends of the pair of bars extend parallel to each 55

other, whereby the prongs formed thereby are spaced from each other. The thickness of the bars 18, as well as the spacing between the prongs is such that said prongs may be inserted in the usual pair of slots 19 of the female portion of an electrical outlet attachment plug 20.

Since one end of each bar is connected with the lug 15 of one of the caps of the lamp and the opposite end is inserted in the electrical outlet attachment plug 20, it is obvious that the electrical current is conducted to the terminals 11 of the lamp, whereby said lamp is illuminated when the plug is placed in an electrical outlet socket. The electrical conductor bars 17, which 15 form the bracket, are covered with a suitable insulating material 21 such as rubber.

From the above, it will be seen that a cheap and inexpensive bracket, by which the "Lumiline" lamp may be directly connected with the ordinary outlet attachment plug is had. The prongs 18 of the bracket may be readily inserted in, or removed from, the plug and, thus, attachment or detachment of the lamp may be quickly accomplished. Since the arms of the bracket are 25 rigidly secured to the lugs 15 which are an integral part of the removable caps 13, it is obvious that the lamp 10 may be removed from the caps without disturbing the bracket. Thus, if the lamp burns out or if, for any reason, replacement is necessary, such replacement may be readily made.

Although the bracket may be utilized for attaching the lamp to any ordinary outlet terminal, it has been found particularly useful in 35 mounting the "Lumiline" lamps on electric signs. It is well known that the sign receptacles or outlet terminals of electric signs are not equally spaced on all signs and usually they vary from 5 to 8 inches apart. "Lumiline" lamps are made in standard lengths of 12 and 18 inches, and thus it will be seen that when the lamps are placed end to end in longitudinal alignment to 40 form a portion of a letter, it is not possible to position the lamps so that a receptacle will be located directly midway between the ends of each lamp. The present invention, however, takes care of such contingency, as will be presently explained.

In Figure 4, three "Lumiline" lamps are shown 50 placed end to end in longitudinal alignment. The outlet receptacles or plugs A of the sign are ordinarily spaced about 7 inches apart, and, therefore, it will be seen that it is impossible to space the lamps so that a receptacle is located centrally 55 with relation to each lamp. In such case, one of the arms 17 of the bracket of each lamp is shortened so as to reach the nearest receptacle. Thus, the prong of this arm is engaged in one of the slots of said receptacle to connect the lamp with one side of the electrical circuit. The other arm 60 17 of the bracket is of such length as to engage the receptacle nearest this end of the lamp, and its prong engages one slot of the nearest receptacle, whereby the circuit to the lamp is completed. It would be possible, however, to construct one arm longer than the other (Figure 6) 65 so that the prongs of both brackets engage the same receptacle. In such case, it is only necessary to lengthen one of the bars and shorten the other, and then bend said bars to form the prongs 18. With such arrangement, said prongs may be formed at any point along the length of the lamp, whereby the lamps may be placed end to end, and electrically connected to the present wiring

systems including outlets or receptacles, irrespective of the position of said outlets or receptacles. It is noted that the bracket not only serves as a support for the lamp but forms the electrical conductor for connecting the lamp with the outlets. 5

In Figure 7, another method of securing the bracket to the cap of each lamp is shown. In this form, each bar 17 is hingedly secured by a pin or rivet 25 to the ear 15 of the cap, but with 10 a sufficient tightness to support the weight of the lamp, yet it is forcibly movable for adjustment. With such arrangement the lamp can be swung a limited distance with relation to the bracket, so that when several lamps are in alignment and any one lamp burns out, the burned out lamp may be swung out of alignment with the others to permit removal and replacement of said lamp.

What I claim and desire to secure by Letters 20 Patent, is:

1. A supporting bracket for an elongate tubular lamp including a pair of arms similar in all respects and designed to mate to form the bracket, each arm formed of flat stock having one end 25 bent at right angles to form a flat prong to be inserted in an electric plug receptacle, its other end being bent at right angles oppositely disposed to the first mentioned end and shaped to form an annular member adapted to engage one 30 end of said lamp, the construction being such the two arms, each connected to its respective end of the tubular lamp and having its inner end inserted in an electric plug, mating to form the support for the lamp, and insulation on said 35 arms between their ends.

2. A supporting bracket for an elongate tubular lamp including a pair of arms similar in all respects and designed to mate to form the bracket, each arm formed of flat stock having one end 40 bent at right angles to form a flat prong to be inserted in an electric plug receptacle, its other end being bent at right angles oppositely disposed to the first mentioned end and shaped to form an annular member provided with a spring 45 tension for snapping in position on one end of said lamp, the construction being such the two arms, each connected to its respective end of the tubular lamp and having its inner end inserted in an electric plug, mating to form the 50 support for the lamp, and insulation on said arms between their ends.

3. A supporting bracket for an elongate tubular lamp of the type having a metallic terminal having a central recess at each end, consisting 55 of a pair of separate electrical current conducting bars extending in opposite directions from each other, each bar at its outer end having a relatively short forwardly directed electrical terminal facing the terminal on the other bar and having contact means consisting of a substantially flat contact with projecting spring fingers frictionally engaging the metallic terminals of the lamp, a cap of insulating material enclosing each of the electrical contact means on the bracket bars and the ends of the tubular lamp, whereby 60 the lamp is supported by the bars and in close proximity thereto, and rearwardly directed flat contact prongs on the adjacent inner ends of the bars to plug in an electric outlet and thereby 65 maintain the bars in their lamp supporting bracket formation.

VAN L. VENDOPE.
